CYRIL T. WALLIS, OF ROCHESTER, NEW YORK, ASSIGNOR TO NORTH EAST ELECTRIC COMPANY, OF ROCHESTER, NEW YORK, A CORPORATION OF NEW YORK.

TEMPERATURE COMPENSATION.

Application filed May 7, 1923. Serial No. 637,394.

This invention relates to the compensation of electromagnetic instruments for the effect of temperature-changes.

In an electromagnetic instrument in which the effect of a current of electricity, flowing in or producing a magnetic field, is to be measured, or to be utilized directly or indirectly in the measurement of some other quantity, it is usually necessary or preferable to use a conductor, for such current, of some relatively low-resistance metal, such as copper or aluminum. Such metals have relatively high temperature coefficients of resistance, and in the use of such instruments inaccuracy may arise from changes in the resistance of the conductor due either to changes in atmospheric temperature or to the direct heating of the conductor by the current flowing in it.

To compensate automatically for such changes in resistance, it has heretofore been proposed to utilize, in the magnetic circuit of an electromagnetic instrument, a shunt consisting of an alloy having the characteristic that its permeability decreases with rise in temperature. Such a shunt acts to diminish the strength of the field, with diminishing temperature in the instrument, more or less in proportion as the efficiency of the conductor increases with the corresponding diminution of resistance.

The alloys best known, heretofore, for the purpose, are certain alloys of nickel and iron. In these alloys however, the temperature-reluctance curve is not a straight line, owing to the fact that the reluctance increases more rapidly, with increase in temperature, in the lower range of atmospheric temperatures than it does in the higher range. The resistance of copper and other metals follows a substantially straight line, however, throughout the ordinary range of atmospheric temperatures, and accordingly a nickel-iron alloy will not give exact temperature-compensation in an electromagnetic instrument, but only a rough approximation to this result.

The object of the present invention is to provide a magnetic shunt which will give substantially perfect compensation throughout a substantial range of temperatures, and particularly a shunt having a substantially straight temperature-reluctance line. I have discovered that this can be accomplished by the use of a shunt consisting of

bodies of two different alloys, the alloys being so chosen that the characteristic line of the one alloy is curved in the opposite direction from that of the other alloy, within the designated range of temperatures, and the two alloys being used in such proportions that the joint effect is a uniform or straight-line change of reluctance with temperature.

The alloys which I have found most suitable for the purpose in question are a nickel-iron alloy having approximately 28.78% of nickel, and the alloy of nickel and copper commonly known as Monel metal. Both of these alloys contain also a small percentage of manganese, which seems to have an obscure relation to their magnetic qualities, but is in any case important for metallurgical reasons.

In a magnetic field having a density of 100 lines per square centimeter, the two alloys in question should be used in about the proportions of 64% nickel-iron and 36% Monel-metal, and as so used their combined permeability follows a line which is straight, within the limits of error in measurement, through a range of 0° to 120° Fahrenheit or more.

In the accompanying drawings Fig. 1 is a diagram showing the permeability of the compensating device of the present invention, and of its separate elements, at various temperatures. Fig. 2 is a diagrammatic view of a portion of a magnetic measuring instrument embodying the present invention. Fig. 3 and Fig. 4 are diagrammatic views showing, respectively, a magnetic relay or regulator and a tachometer compensated in accordance with this invention.

In Fig. 1 the abscissæ of the curves are temperatures, while the ordinates represent the flux-density in the compensating bodies when subjected to a magnetic field of constant strength, at the several given temperatures. From this diagram it will be apparent that the temperature-permeability of the nickel-steel follows an upwardly concave curve, while the corresponding line of the Monel metal is oppositely curved, and that these opposite curvatures combine in a sum or resultant which is approximately straight through the range from 0° to 120° Fahrenheit.

This compensating device may be used in electromagnetic instruments of various

types. Fig. 2 shows its application to an electrical measuring instrument such as a voltmeter or ammeter, provided with a permanent magnet 5, which is used to produce a field in which a coil or armature (not shown) may move. When not compensated for temperature, such an instrument must be used in an atmosphere of definite temperature, in order that its reading may be accurate, and the current passed through its coil must be so small as not sensibly to heat the coil. These limitations may be removed, however, by the use of a compensating shunt between the poles of the magnet. 15 This shunt is shown as comprising a cylindrical core 6 of nickel-steel, and a surrounding shell 7 of Monel-metal.

A relay or regulator may be compensated, as set forth in United States Letters Patent 20 to Thomas L. Lee, No. 1,398,463, by a magnetic shunt between the polar extremities of its electromagnet, and as shown in Fig. 3 the shunt may consist, in accordance with the present invention, of superposed plates 25 8 and 9 of the two alloys.

Fig. 4 shows the invention as utilized in a magnetic tachometer, in which an indicator cup 10, turning on an axis 11, is moved by the inductive drag of a ring-shaped permanent magnet 12 which is rotated upon a shaft 13. The compensating alloys 14 and 15 are interposed in a gap in the ring-magnet, the magnet being so magnetized that its extremities 16 and 17 constitute its poles. In this 35 instance the two alloys are shown as arranged so as to be traversed in series by the magnetic flux, but obviously they may be used in parallel instead, as shown in Figs. 2 and 3.

It will be understood that the several specific instances of the use of this invention which have been shown and described are only a few among many possible uses. It will also be apparent that while the alloys used may, and usually will be so selected and proportioned as to secure an approximate

straight-line resultant, as in Fig. 1, the invention is not limited to such use. By suitable selection and proportions the dissimilar alloys may be caused to secure a resultant 50 following a curve of almost any desired form, and the novel and valuable nature of the invention resides in the fact that it permits the automatic compensation of an instrument according to a law or laws which 55 are not limited to the idiosyncrasies of any particular metal or alloy.

The lines given in Fig. 1 were obtained in a magnetic field having a density of 100 lines per square centimeter. In a field of 60 different strength it may be necessary to use the dissimilar alloys in proportions different from those shown. This is a matter which 65 may readily be determined by experiment in any given case.

The invention claimed is:

1. Means, for compensating for the effect of temperature changes in an electromagnetic instrument, comprising bodies of dissimilar magnetic alloys located in a magnetic circuit of the instrument, said alloys being such that their temperature-permeability lines are oppositely curved through a substantial range of temperatures. 70

2. In an electromagnetic instrument, the 75 combination, with a magnet, of a magnetic shunt associated therewith and comprising bodies of two dissimilar alloys such that their temperature-permeability lines are oppositely curved so as to produce a resultant 80 approximating a straight line.

3. In an electromagnetic instrument, the 85 combination, with a magnet thereof, of a magnetic compensating device comprising two bodies of dissimilar alloys located between the poles of said magnet, said alloys having different temperature - permeability characteristics so as to compensate the instrument in accordance with a law different 90 from that of either alloy. 20
